(57) **CLAIM**

The ornamental design for a resin panel with sector design, as shown and described.

DESCRIPTION

FIG. 1 is a front perspective view of a resin panel with sector design as used in a partition structure, wherein the sector design is printed on a front surface of the resin panel; FIG. 2 is a top, right, front perspective view thereof; FIG. 3 is a front elevational view thereof; FIG. 4 is a left side elevation view taken along line 4-4 of FIG. 3; FIG. 5 is a right side sectional view taken along line 5-5 of FIG. 3; FIG. 6 is a top sectional view taken along line 6-6 of FIG. 3; and FIG. 7 is a bottom sectional view taken along line 7-7 of FIG. 3;

FIG. 8 is a top, right, front perspective view of an alternative embodiment of a resin panel with sector design wherein the design comprises an interlayer between two resin panels; FIG. 9 is a front elevational view thereof; FIG. 10 is a left side elevation view taken along line 11-11 of FIG. 9;

FIG. 11 is a right side sectional view taken along line 12-12 of FIG. 9; FIG. 12 is a top sectional view taken along line 12-12 of FIG. 9; and, FIG. 13 is a bottom sectional view taken along line 13-13 of FIG. 3.

The broken lines in the drawings depict environmental subject matter only and form no part of the claimed design.
